CLAIM

The ornamental design for the archery glove, as shown and described herein.

DESCRIPTION

FIG. 1 is a top view of an archery glove in accordance with the claimed design;

FIG. 2 is a top perspective view of the archery glove in a first gripping position;

FIG. 3 is an additional top view of the archery glove;

FIG. 4 is a side view of the archery glove viewing the thumb-side of the glove;

(Continued)

FIG. 5 is a side view of the archery glove opposite the view shown in FIG. 4 viewing the fifth digit or pinkie-side of the glove; and,

FIG. 6 is a front view of the archery glove with the fingers and thumb of the glove in a second gripping position, showing a portion of the glove in a curled position.

The broken lines shown in FIGS. 1-6 illustrate a hand or arm and form no part of the claimed design.

1 Claim, 6 Drawing Sheets
